Chas. C. Gill

UNITED STATES PATENT OFFICE.

FRANK A. WEEKS, OF PLAINFIELD, NEW JERSEY.

INKSTAND.

1,347,527.

Specification of Letters Patent. Patented July 27, 1920.

Application filed December 24, 1917. Serial No. 208,674.

To all whom it may concern:

Be it known that I, FRANK A. WEEKS, a citizen of the United States, and a resident of Plainfield, in the county of Union 5 and State of New Jersey, have invented certain new and useful Improvements in Inkstands, of which the following is a specification.

The invention resides in a novel construction of two-piece inkstands, one piece being the base containing the ink-well and the other the cover for said well.

In accordance with my invention, the base has a flat bottom and a top which is of convex outline, being on the arc of a circle, and centrally of the base is formed the ink-well which opens into a dip-chamber adapted to receive a pen when necessary. The base is also formed at opposite sides of the ink-well 20 with shoulders which project upwardly and are of suitable character to cooperate with the cover and serve as stops for the same when the cover is in its open and closed positions. The base will preferably be in one 25 integral piece of glass or other suitable material. The cover is of arc outline and at its edges is formed with downwardly extending flanges which have the same curvature as the top of the base, and said cover 30 is adapted to have a sliding movement on the curved top of the base, being moved rearwardly, when it is desired to expose the dip-chamber, and frontwardly, when it is intended to close said dip-chamber. The 35 cover is guided in its sliding movements by the shoulders at the opposite sides of the ink-well, and said shoulders are engaged by the front and rear flanges, respectively, on the cover in arresting said cover at its 40 open and closed positions. The cover is in one integral piece and may be of any suitable composition or other material.

One object of the invention is to provide an inkstand of very neat and attractive appearance and one whose parts may be readily manufactured and assembled and also readily cleaned whenever desired. A further object of the invention is to provide an inkstand affording great convenience to the 45 user and which while possessing other characteristics, is of the slide-cover type.

The invention will be fully understood from the detailed description hereinafter presented, reference being had to the accompanying drawings, in which:

Figure 1 is a perspective view of an inkstand constructed in accordance with and embodying the invention;

Fig. 2 is a top view, on a larger scale, of the same;

Fig. 3 is a vertical transverse section through the same, taken on the dotted line 3—3 of Fig. 2, and

Fig. 4 is a vertical transverse section through the same, taken on the dotted line 4—4 of Fig. 2.

In the drawings, 10 designates the base of the inkstand, 11 the ink-well therein, and 12 the cover adapted to close said well or expose the same, as may be required. The 70 base 10 may be formed of glass or other material and may contain one ink-well 11 or a plurality of ink-wells, it being my intention to make the base for a single inkstand or for a double inkstand or for a treble 75 inkstand, to meet the several requirements of the trade.

In the present instance 10 illustrates a base having two ink-wells 11, an intermediate tray 30 and a pen-rack 13, but I do not 80 confine the invention to the presence of the tray 30 or the pen-rack 13 or to a plurality of ink-wells 11, since one end portion of the base, say the left hand portion, shown in Fig. 1, up to the line 14, would constitute 85 a single inkstand and embody my invention. The base 10 has a flat bottom and an arcuate or upwardly convexed upper surface 15, and at the center of the upwardly convexed surface 15 is formed the ink-well 11 which is 90 of circular outline and entirely open at its top, and said ink-well 11 communicates through a narrow open throat 16 with a forwardly disposed dip-chamber 17, into which a pen may be dipped to receive ink. 95 At opposite sides of the ink-well 11 the upper surface 15 of the base is formed with upwardly extending transverse shoulders 18, which serve as guides and stops for the cover 12, as hereinafter explained. The 100 base 10 is in one integral piece and may be handled as a unit, and it is essential in the carrying out of my invention that said base be formed with the arcuate upper surface 15.

The cover 12 is in one integral piece of 105 molded composition or other suitable material and it is of arcuate shape and adapted to fit snugly upon the upper surface 15 of the base 10. The cover 12 has a smooth upwardly convexed top and downwardly ex- 110

tending side and end flanges 19, 20, respectively, whose lower edges conform to the upper surface of the base 10 and are adapted to ride smoothly and evenly thereon.

5 The side flanges 19 embrace, with reasonable snugness, the shoulders 18 formed on the base 10, and said cover 12 is adapted to have a sliding movement rearwardly and forwardly on the base 10 while guided by 10 the shoulders 18. The front flange 20 of the cover 12 is adapted to engage the front ends of the shoulders 18 when said cover is pushed rearwardly to expose the dip-chamber 17, said flange 20 and the front ends of 15 the shoulders 18 then serving as stops to arrest said cover and prevent it from riding down from off the base 10. When the cover 12 is moved forwardly to conceal the dip-chamber 17, as shown at the right hand side 20 of Fig. 2, and also in Fig. 3, the rear ends of the shoulders 18 may serve to arrest said cover and prevent it from sliding downwardly from off the base or to a point at which it might expose the rear edge of the 25 well 11. The shoulders 18 are of a length about equal to the diameter of the well 11, less the dip-chamber 17, as clearly illustrated, and hence the cover 12 is adapted to have a sliding movement only to a sufficient extent to expose or cover the dip-chamber 30 17. The cover 12 is in one integral piece and may be dropped upon the base 10 and also readily removed therefrom. The inkstand is composed of two essential 35 parts, to-wit, the base 10 and cover 12, and these two parts may be readily separated or combined, and they both present smooth exterior surfaces which may be readily cleansed whenever required. I 40 preferably curve the middle portions of the front and back edges of the cover 12 outwardly, as shown, both for neatness of appearance and to make it unnecessary to slide the cover either frontwardly or rearwardly to any unnecessary extent in covering or uncovering the dip-chamber 17 or concealing the rear edge of the well 11. The ends of the base 10 are flat, as shown. 45 The curvature of the upper surface of the base 10 and the like curvature of the cover 12 result in the base and cover being harmonized in appearance and in both being able to avoid undue accumulation of dust and the like, and further it may be said 50 that the well 11 is at the apex of the base 10, and hence may be of adequate capacity for holding ink, without the base requiring an undue amount of glass or other material 55 in its construction. The dip-chamber 17 is 60 a part of the well 11 and is on the front slope of the curved surface 15 of the base, and hence may be conveniently reached by a pen. The narrow throat 16 is of importance, because with the presence of the dip-chamber 17 and narrow throat 16 only a 65

small surface of the ink is exposed when the cover 12 is in its open position, and in addition the surfaces at the edges of the throat 16 serve to prevent a pen from sliding unduly inwardly into the well 11 when the 70 pen is dipped into the ink. The ink-well may therefore be said to be at the apex of the curved surface 15 of the base, but having a forwardly extending portion on the front slope of said apex for the convenience 75 of the user of the inkstand.

What I claim as my invention and desire to secure by Letters-Patent, is:

1. An inkstand comprising a base in one integral piece having an upwardly convexed upper surface and containing an ink-well and forwardly disposed dip-chamber communicating with said well and also having at opposite sides of said well transversely disposed shoulders, and a cover conforming to the arcuate outline of the upper surface of said base and having side and end depending flanges engaging the top surface of said base, the side flanges of said cover embracing said shoulders and said shoulders being spaced apart a less distance than the end depending flanges of said cover and adapted on the arcuate movement of said cover to arrest the same in its open and closed positions. 95

2. An inkstand comprising a base in one integral piece having an upwardly convexed upper surface and containing at the apex thereof an ink-well, said base having at opposite sides of said well transversely disposed shoulders, and a cover conforming to the arcuate outline of the upper surface of said base and having side and end depending flanges engaging the top surface of said base, the side flanges of said cover embracing said shoulders and said shoulders being spaced apart a less distance than the end depending flanges of said cover and adapted on the arcuate movement of said cover to arrest the same in its open and closed positions. 100

3. An inkstand comprising a base in one integral piece having an upwardly convexed upper surface and containing at the apex thereof an ink-well having a forwardly disposed portion at the front slope of said surface, and a cover conforming to the arcuate outline of the upper surface of said base and adapted to have rearward and forward sliding movement thereon and being 115 capable of being lifted bodily therefrom, said base and cover having interengaging portions for arresting said cover at the ends of its rearward and forward movements, and said cover when in its forward position being adapted to cover said well. 120

4. An inkstand comprising a base in one integral piece having an upwardly convexed upper surface and containing at its apex an ink-well having a forwardly dis- 130

posed dip-chamber communicating therewith, and a slide-cover adapted to the arcuate outline of the upper surface of said base and being capable of being lifted bodily therefrom, said base and cover having interengaging portions for arresting said cover at the ends of its rearward and forward movements, and said cover when in its forward position being adapted to cover

5 said dip-chamber and when in its rear position to expose the same.

10 5. An inkstand comprising a base in one integral piece having an upwardly convexed upper surface and containing at its apex an ink-well, and a slide-cover adapted

15 to the arcuate outline of the upper surface of said base and being slidable transversely

thereon and also capable of being lifted bodily therefrom, said base and cover having interengaging portions for arresting 20 said cover at the ends of its rearward and forward movements, and said cover when in its forward position being adapted to cover said ink-well and when in its rear position to expose a portion only of the 25 same.

Signed at New York city, in the county of New York and State of New York, this 22nd day of December A. D. 1917.

FRANK A. WEEKS.
